United States Patent Office

Des. 187,208
Patented Feb. 9, 1960

187,208

SHAPED PIECE OF PRINTED TEXTILE FABRIC

Huguette Braverman, Forest Hills, N.Y., assignor to Edward H. Moss, New York, N.Y.

Application April 3, 1957, Serial No. 45,576

Term of patent 3½ years

(Cl. D92—1)

The figure is a plan view of a shaped piece of printed textile fabric showing my new design.

I claim:

The ornamental design for a shaped piece of printed textile fabric, substantially as shown.
